UNITED STATES PATENT OFFICE.

ALLEN A. TIRRILL, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRICAL REGULATOR.

1,147,575.

Specification of Letters Patent. Patented July 20, 1915.

Application filed March 3, 1914. Serial No. 822,133.

To all whom it may concern:

Be it known that I, ALLEN A. TIRRILL, a citizen of the United States, and a resident of Pittsburgh, in the county of Allegheny and State of Pennsylvania, have invented a new and useful Improvement in Electrical Regulators, of which the following is a specification.

My invention relates to electrical regulators, and particularly to those in which the voltage of a generator is regulated by opening and closing a shunt to a resistance included in series with the field of the exciter for the generator.

The object of my invention is to provide a regulator of the character indicated that shall be exceptionally effective, accurate and reliable in operation.

My invention is illustrated in the accompanying drawings, Figure 1 of which is a top plan view of a regulator constructed in accordance therewith; Fig. 2 is a front face and sectional view of the regulator of Fig. 1; Fig. 3 is a plan and sectional view of a resilient stop device constituting a part of the regulator; Fig. 4 is a side view of the regulator, and Fig. 5 is a diagram illustrating the circuit connections of the regulator when employed in connection with a generator.

The regulator comprises a cast metal base 1 that is provided upon its rear with threaded studs 2 by means of which it may be secured to a panel (not shown) or any other suitable support, and that is also provided upon its front face with brackets 3 and 4. Pivotedly mounted in the bracket 3 is a bell crank lever 5, one arm of which is substantially horizontal and the other substantially vertical arm of which is bifurcated at its lower end. The bifurcations of the lever 5 are provided with screws 6 and 6^a that are adapted to engage opposite faces of a plate spring 7 that is mounted between the bifurcations or arms of a stationary lug or post 8. The said parts constitute resilient means to limit the movements of the lever 5, for reasons which will be hereinafter fully explained, the limits of the movement being determined by adjustment of the screws 6 and 6^a. A spring 9 serves to normally draw the vertical arm of the lever 5 toward the right. The horizontal arm of the lever 5 is also forked or bifurcated, and is provided with bearings for the pivot pins 10 of an-

other bell crank lever 11, one arm of which is curved and somewhat inclined and is provided, near its free end, with a screw 12 that constitutes a contact terminal adapted to engage and disengage a corresponding opposite contact terminal 13. The contact terminal 13 is carried by a plate spring 14 that is mounted upon a stud 15 carried by the base 1. The movements of the contact terminals are limited by means of screws 16 and 17 that are threaded in a bifurcated stationary support 18. One arm of the lever 11 is substantially vertical and comprises a magnetizable core 20, the lower end of which is operatively connected to the piston of a dash pot 21. The lower end of the core member 20 is surrounded by a coil 22 that is mounted in curved brackets 23 carried by the base 1. When the coil 22 is energized, the core 20 is drawn downwardly, thereby causing the lever 5 to rotate about its fulcrum and also causing the contact members 12 and 13 to disengage. When, however, the coil 22 is deenergized or is not sufficiently energized, the spring 9 overcomes the pull of the coil upon the core 20 and the contact terminals 12 and 13 are caused to engage.

The substantially vertical arm of the lever 11 and the coil 22 are surrounded by a frame 25 or yoke 25 that is pivotally mounted, near its upper end, in the bracket 4, and to the lower end of which the cylinder of the dash pot 21 is secured, the pivot of the said frame being normally substantially in alinement with the pivot of the lever 11. The upper end of the frame 25 is attached to a substantially horizontal lever 26 from one end of which a core member 27 is suspended, a dash pot 28 being employed for the purpose of damping the movements of the core member and the lever 26. At the opposite end of the lever 26 an adjustable counter-weight 29 is suspended, a spring 30 being interposed between the counter-weight and the lever, and a guide 31 being provided at the lower end of the counterweight for preventing its swinging. The counterweight 29 only partially balances the weight of the parts upon the opposite side of the fulcrum of the lever 26.

The upper end of the core member 27 is surrounded by a coil that comprises two windings 32 and 33 respectively, the former composed of comparatively fine wire and

the other of comparatively heavy wire. As the pull exerted by the windings 32 and 33 upon the core member varies, the bell crank lever, composed of the members 25 and 26, 5 is rotated about its pivot, and the bell crank lever 11 is correspondingly rotated by reason of the connection therewith of the frame 25 through the dash pot 21. Consequently, the distance between the contact terminals 12 10 and 13 varies with the degree of pull exerted by the coils 32 and 33 upon the core member 27. The number of effective turns of the winding 33 may be adjusted by means of two rotatable arms 34 and 35 that are pivotally mounted upon a small panel carried by 15 the same supports as carry the coils, the arm 34 being employed for adjusting the number of turns in the outer layer, and the arm 35 for adjusting the number of layers in the 20 coil.

A system in connection with which the regulator may be conveniently employed is shown in Fig. 5, in which a generator 40 supplies current to bus bars 41 to which any 25 suitable number of lighting, or other distributing circuits, may be connected such as that shown at 42. The generator 40 is provided with a field magnet winding 43 that is supplied from exciter bus bars 44 to which 30 current is in turn supplied from an exciter 45 having a shunt field magnet winding 46 in series with which is a rheostat 47. The winding 32 is supplied with current from a potential transformer 48, the primary winding 35 of which is connected to the bus bars 41 in such a manner that the current supplied to the said coil will vary with the potential of the bus bars. The winding 33 is supplied with current from a series transformer 40 49, the primary winding of which is connected in series with one of the conductors of the distributing circuit 42. The coil 22 is supplied with current from another potential transformer 50 that is also connected 45 to the main bus bars 41. The circuit including the coil 22 and the secondary winding of the transformer 50 is adapted to be periodically opened and closed by means of a relay 51 having contact terminals 52 and 53. The 50 relay 51 has an energizing winding 54 that is supplied with current from the exciter bus bars 44 and is adapted to vibrate the contact terminals 52 and 53 into and out of engagement. A circuit in shunt to the exciter field rheostat 47 is opened and closed 55 by means of contact terminals 55 and 56 of a relay 57 that is similar to the relay 51 and is provided with an energizing coil 58 that also receives current from the exciter bus 60 bars. The contact terminals 12 and 13 are respectively connected to the terminals of the coils 54 and 58 of the relays 51 and 57 so that the engagement and disengagement of the said contacts serve to close and open a 65 shunt circuit to the said relay coils.

If, in the operation of the device, the contact terminals 12 and 13 are not in engagement, the relay coils 54 and 58 are fully energized and thus cause the relay contact terminals to disengage. Upon disengagement 70 of the terminals 52 and 53 the circuit of the coil 22 is opened and the core member 20 is moved upwardly by the spring 9 and causes the contact terminals 12 and 13 to engage. Upon engagement of the contact terminals 75 12 and 13, the relay coils 54 and 58 are shunted and the relay contact members thereupon engage. Engagement of the contact terminals 52 and 53 establishes the circuit of the coil 22 which thereupon attracts 80 the core member 20 and the contact terminals 12 and 13 disengage. Engagement of the contact terminals 55 and 56 of the relay 57 results in shunting the exciter field rheostat, while disengagement thereof results in 85 removing the said shunt. The effective resistance in the exciter field circuit depends upon the relation of the periods of engagement to the periods of disengagement of the contact terminals 55 and 56, and the exciter 90 and generator field strengths and voltages likewise depend thereon. This relation of the periods of engagement and disengagement is determined by the voltage of the generator or of the main bus bars and by 95 the current delivered to the distributing circuit 42, since the initial distance between the contact terminals 12 and 13 depends upon the degree of pull exerted thereby upon the core member 27. Thus, it will be seen that 100 the coil 22 serves to cause the contact terminals 12 and 13 to engage and disengage, while the coils 32 and 33 vary the initial distance between the said terminals so as to obtain varying periods of engagement and 105 disengagement. The coil 33 is arranged to act in opposition to the coil 32 in order to compensate for drop in voltage in the distributing circuit, that is, so that the voltage at the distant end of the distributing circuit 110 may be properly maintained.

The movements of the lever 5 are limited by the spring 7 for the purpose of permitting of readily cutting the regulator in and out of service, which is accomplished by decreasing the actual value of the resistance 47 in the exciter field circuit. It will be understood that the resistance 47 normally has an actual value in excess of that which would cause the generator voltage to assume 120 its normal value. This is because the effective value of the said resistance is determined by opening and closing a shunt circuit thereto and is, accordingly, less than its actual value. In order to cut the regulator out of service, the actual value of the resistance 47 should be reduced to correspond with its effective value when the generator voltage is normal. The effect of reducing the actual value of the said re- 125 130

sistance is to cause a tendency of both the exciter and generator voltages to increase, the actual increase, however, being comparatively slight because the regulator contact members continue to vibrate into and out of engagement. On account of the tendency of the generator voltage to increase, the coil 32 tends to cause the contact members 12 and 13 to separate, with the result that the periods of disengagement of said members become longer than the periods of engagement, and also that the relay contact members 52-53 and 55-56 engage for shorter periods and disengage for longer periods. The coil 22 is, consequently, energized for shorter periods and the spring 9 tends to cause the contact member 12 to engage the member 13 and the screw 6 to approach the spring 7. As the resistance 47 is reduced in value the screw 6 finally engages the spring 7, which thereupon opposes the spring 9 and ultimately prevents it from causing the members 12 and 13 to engage. The coil 22 cannot then be energized and the regulator ceases to operate. It may then be cut out of service. When the spring 7 is engaged by the screw 6^a, it assists the spring 9 in causing engagement of the contact terminals 12 and 13. The screws 6 and 6^a are so adjusted that only very slight variations in the voltage can occur under widely different conditions of operation.

I claim as my invention:

1. An electrical regulator comprising co-operating contact members, an arm actuating one of said members, a lever upon which the said arm is fulcrumed, a winding for actuating the said arm and lever to cause the contact members to engage and disengage, a second lever for actuating the contact actuating arm to vary the distance between the contact members, and a winding for actuating the said second lever.

2. An electrical regulator comprising co-operating contact members, an arm actuating one of said members, a lever upon which the said arm is fulcrumed, a winding for actuating the said arm and lever to cause the contact members to engage and disengage, a second lever for actuating the contact actuating arm to vary the distance between the contact members, the fulcrum of the said second lever being substantially in alinement with that of the contact actuating arm, and a winding for actuating the said second lever.

3. An electrical regulator comprising co-operating contact members, a bell-crank lever for actuating one of the said members and having a depending arm, another lever upon which the aforesaid lever is fulcrumed, a winding for actuating said levers to cause the contact members to engage and disengage, a third lever connected to the depending arm of the contact carrying lever

and adapted to vary the distance between the contact members, and a winding for actuating the said third lever.

4. An electrical regulator comprising co-operating contact members, a bell-crank lever carrying one of said members and having a depending arm, another lever upon which the aforesaid lever is fulcrumed, a winding for actuating the said levers to cause the contact members to engage and disengage, a third lever connected to the depending arm of the contact-carrying lever and adapted to vary the distance between the contact members, the fulcrum of the said third lever being substantially in alinement with that of the contact-carrying lever, and a winding for actuating the said third lever.

5. An electrical regulator comprising co-operating contact members, a bell-crank lever carrying one of said members and having a depending arm, another lever upon which the aforesaid lever is fulcrumed, a winding for actuating the said levers to cause the contact members to engage and disengage, a third lever having a depending arm in the form of a yoke that surrounds the said winding and engages the depending arm of the contact-carrying lever, and a winding for actuating the said third lever.

6. An electrical regulator comprising co-operating contact members, a bell-crank lever carrying one of said members and having a depending arm, another lever upon which the aforesaid lever is fulcrumed, a winding for actuating the said levers to cause the contact members to engage and disengage, a third lever having a depending arm in the form of a yoke that surrounds the said winding and engages the depending arm of the contact-carrying lever, the fulcrum of the said third lever being substantially in alinement with that of the contact-carrying lever, and a winding for actuating the said third lever.

7. An electrical regulator comprising co-operating contact members, a bell-crank lever carrying one of said members and having a depending arm provided with a magnetizable core, another lever upon which the aforesaid lever is fulcrumed, a coil surrounding the said magnetizable core, a third lever also having a depending arm that engages the depending arm of the contact-carrying lever, and a winding for actuating the said third lever.

8. An electrical regulator comprising co-operating contact members, a bell-crank lever carrying one of said members, another lever upon which the aforesaid lever is fulcrumed, means for resiliently limiting the movements of the latter lever, a winding for actuating the said levers to cause the contact members to engage and disengage, a third lever for actuating the contact carry-

ing lever to vary the distance between the contact members, and a winding for actuating the said third lever.

9. The combination with a dynamo-electric machine, of a regulator therefor comprising coöperating contact members, a lever carrying one of said members, another lever upon which the aforesaid lever is fulcrumed, a winding for actuating the said levers, 10 means for causing the said winding to be intermittently energized, a third lever for actuating the contact-carrying lever, and a winding for actuating the said third lever in response to variations of an electrical condition 15 of the dynamo-electric machine.

10. An electrical regulator comprising coöperating contact members, an electromagnet and resilient means adapted to cause said members to engage and disengage, resilient 20 means for limiting the relative movements of the contact members in both directions, and means for varying the initial distance between the contact members.

11. An electrical regulator comprising coöperating contact members, an electromagnet and resilient means adapted to cause said members to engage and disengage, resilient means for limiting the relative movements of the contact members, and means for varying 30 the initial distance between the contact members.

12. An electrical regulator comprising coöperating contact members, a lever actuating one of said members, an electromagnet and 35 resilient means for vibrating said lever to cause the said members to engage and disengage, resilient means for limiting in both directions the relative movements of the contact members caused by said electromagnet 40 and resilient means, and means for adjusting

the position of the said lever to vary the initial distance between the contact members.

13. An electrical regulator comprising coöperating contact members, a lever actuating one of said members, an electromagnet and resilient means for vibrating said lever to cause the said members to engage and disengage, resilient means for limiting the relative movements of the contact members 50 caused by said electromagnet and resilient means, and means for adjusting the position of the said lever to vary the initial distance between the contact members.

14. An electrical regulator comprising coöperating contact members, an electromagnet and resilient means adapted to cause said members to engage and disengage, resilient means for limiting relative movements of the contact members caused by the aforesaid 60 resilient means, and means for varying the initial distance between the contact members.

15. An electrical regulator comprising coöperating contact members, an electromagnet and resilient means adapted to cause said members to engage and disengage, the said members controlling the energization of the electromagnet, resilient means for limiting the relative movements of the contact members, and means for varying the initial distance 70 between the contact members.

In testimony whereof, I have hereunto subscribed my name this 20th day of Feb., 1914.

ALLEN A. TIRRILL.
